UNITED STATES PATENT OFFICE

ROBERT ERNEST MCFARLAND, OF CICERO, ILLINOIS, ASSIGNOR TO WESTERN ELECTRIC COMPANY, INCORPORATED, OF NEW YORK, N. Y., A CORPORATION OF NEW YORK

STRAND-WORKING MECHANISM

Application filed August 9, 1924. Serial No. 731,199.

This invention relates to strand working mechanisms, and more particularly to a machine for treating strands.

The primary object of this invention is 5 to provide an improved apparatus for uniformly treating a strand or cable.

Other objects and advantages of the present invention will become apparent from the following detailed description and will be 10 particularly pointed out in the appended claims.

The preferred embodiment of the invention comprises a cable painting machine wherein the cable is passed from a supply reel through a paint bath, then through a wiping mechanism which removes all excess paint therefrom, thereby insuring a smooth and even coating while at the same time expediting drying thereof. Means is 15 provided for maintaining the cable in a substantially straight line as it is passed through the paint bath and wiping mechanism thereby avoiding any injury to the cable due to bending or twisting thereof while being 20 treated. Common means is provided for controlling the operation of the wiping mechanism and the movement of the cable therethrough whereby the wiping mechanism is rendered ineffective when the movement of the cable is discontinued.

In the accompanying drawings which illustrate one embodiment of the invention,

Fig. 1 is a vertical section of a cable painting machine embodying the features of 25 the present invention;

Fig. 2 is an end view partly in section approximately on the line 2—2 of Fig. 1;

Fig. 3 is a sectional view taken on the line 3—3 of Fig. 1;

Fig. 4 is a fragmentary detail view of the supply reel brake;

Fig. 5 is an enlarged detail view of the air wiping mechanism; and

Fig. 6 is a fragmentary detail view of the air blast control mechanism.

As shown in the drawings, the machine is preferably built with two units 10 and 11 positioned back to back with a paint container and a main driving means common to 50 both units, and in the following description

it will suffice if the construction and operation of one unit is described. A base or supporting member common to both units is indicated at 12 and suitably carried thereon, and positioned at one end of the machine midway between the two units 10 and 11, is a driving motor 13. Positioned at the opposite end of the machine and suitably supported upon a base 14 is a paint container 15 which supplies paint to both units of the machine. Each unit is provided with a subsidiary paint container 16 which is horizontally disposed near the top of the machine and which is provided with a hinged cover 17 which may be opened to a substantially vertical position against suitable stops 18 as indicated in Fig. 2.

A main driving shaft 20, extending from the motor 13, is journaled in bearings 21, 22 and 23 of a housing or gear box 24 which is supported upon the base 12. Keyed to the main shaft 20, and near the extreme end thereof, is a pinion 25 which meshes with a gear 26 (Fig. 3) keyed to a pump shaft 27, thereby providing means for driving a 70 rotary pump 30 which is supported on a raised portion 31 of the base member 12. The function of the pump 30 is to facilitate filling the main tank 15 with paint from a barrel or other source of supply through a flexible piping indicated at 32. The pump 30 also serves to pump the paint from a tank 15 to the subsidiary tanks 16 through suitable piping indicated at 33. A plurality of drain pipes 28, the openings in which are controlled by valves 29, provide means for maintaining the paint level in the tank 16 constant during the operation of the machine. The operation of the pump 30 is controlled by a valve 34, which controls the 75 passage of paint into the main tank 15 from an outside supply source, and a pair of valves 35 which control the flow of paint from the main tank 15 to the subsidiary tanks 16.

A mixing member 36 is revolvably mounted within the tank 15 and carries a plurality of agitator blades 37, 37 which serve to maintain the paint properly mixed during the operation of the machine. The 90

mixing member 36 is connected to a horizontal shaft 38 by a connecting rod 39 and is driven from the pump shaft 27 by a pinion 40 meshing with a gear 41 keyed to the shaft 38, as clearly shown in Fig. 3. To facilitate thorough cleaning of the tank 15, the mixing member 36 may be removed through an opening 42 in one end of the tank. A removable cover 43 fits over the opening 42 and is tightly secured to the tank 15 by a plurality of bolts 44. The tank 15 may be emptied by the removal of a plug 45 positioned in the bottom thereof.

Brackets 46 are secured to the support 31, one at either side of the pump 30 and rigidly supported in each bracket is a spindle 47 upon which a supply reel 50 is revolvably mounted. A brake drum 49 is revolvably mounted on the spindle 47 and is held in position against the bracket 46. A head 51 of the supply reel is provided with a plurality of apertures 52, either one of which is adapted to be engaged by a pin 53 rigidly secured to the drum 49, which is thereby driven by the supply reel 50. To prevent the supply reel from sliding off during the operation of the machine, the spindle 47 is provided with a circular groove 54 near its end adapted to hold a spring locking pin 55.

A tension arm 56 (as best shown in Fig. 4) is pivoted at 57 to the bracket 46 and carries a guide roller 59 which is positioned to engage the cable 60 as it leaves the supply reel 50. A cam 61 is also pivoted at 57 and is rigidly secured to the arm 56. Pivoted at 62 and positioned to engage the peripheral surface of the brake drum 49 is a suitably lined brake shoe 63. The cam 61 engages the brake shoe 63 and operates to vary the braking effect thereon in response to variations in the tension of the cable as it leaves the supply reel and passes over the guide roller 59. A spring 64 serves to normally hold the brake shoe 63 against the drum 49.

A guide roller 65 is revolvably carried in a bracket 66 which is rigidly secured to the tank 15 by bolts 67. One end of a guard 68 is fastened to the bracket 66 and its other end is secured to the floor by a bracket 69. The purpose of the guard 68 is to prevent the cable from entangling or touching the floor as it is pulled from the supply reel over the guide rollers 59 and 65. A housing or guard 70 fits over the guide roller 65 and is suitably secured to the bracket 66 and the tank 15.

The tank 16 is provided with openings or slots 71 at the front and rear ends through which the cable is passed. The slot 71 extends to approximately the center of the tank 16 and its bottom is in alignment with the top of the guide roller 65. It is therefore apparent that the cable is maintained in a substantially straight line as it is passed

through the center of the tank 16. A roller 72 is mounted in a bracket 73 which is suspended from the cover 17 into the tank 16. The purpose of the roller 72 is to keep the cable submerged in the paint as it is passed through the tank 16. An overflow pipe 74 is positioned at each end of the tank 16 directly below the opening 71, thereby providing means by which the paint is returned to the tank 15.

Upon leaving the tank 16, the cable passes through a surplus paint removing device 75 which is connected with a compressed air line 76 controlled by a valve 77. The device 75 is supported in a housing 78 secured to the tank 16. The construction and operation of the surplus paint removing device 75 is fully disclosed in Patent No. 1,526,071, issued to F. S. Kochenderfer and H. J. Bee, February 10, 1925, and since it forms no part of this invention, it is thought that a further detailed description thereof is unnecessary. Upon leaving the surplus paint removing device 75, the cable passes through an auxiliary surplus paint remover 80 which is also supported in the housing 78 and comprises a clamping device adapted to clamp burlap 81 or other suitable material around the cable as it is passed therethrough.

A guide roller 82 is revolvably mounted in a bracket 83 which may be rigidly secured to or form a part of the housing 78. The painted cable is passed over the guide roller 82 to a take-up reel 85 upon which it is evenly distributed by suitable mechanism indicated at 100. The take-up reel 85 is mounted on a spindle 86 extending from a stud shaft 87 which is supported in bearings 88 and 89 formed in the housing 24. An annular member 90 is keyed to the shaft 87 and its outer surface is provided with a pin 91 which is adapted to engage either one of a plurality of apertures 92 in the take-up reel head 93, thereby making the take-up reel rotatable with the shaft 87. The driving member 94 of a clutch 95 is rotatably mounted on the shaft 87 and keyed to the clutch members 94 of both units of the machine is a sleeve 96. A worm gear 97 is keyed to the sleeve 96 and meshes with a worm 98 keyed to the main driving shaft 20. From the above description it is apparent that the driving member 94 of the clutch 95 is driven directly from the main shaft 20.

The driven member 99 of the clutch 95 is keyed to the shaft 87 and is longitudinally slidably thereon. Secured to the clutch member 99 is a movable member 101 of an annular brake 102, its stationary member 103 being rigidly secured to the housing 24. A yoke member 105 straddles the movable clutch member 99 and is keyed to a shaft 106 rotatably mounted in bearings 107, 108 and 109 formed in the housing 24. The lower end of a vertically disposed arm 110 is keyed

to the shaft 106 and its upper end is pivoted at 111 to a horizontal bar 112, which is slidably supported in the housing 24. A handle 113 is provided at the outside end of the bar 112 by which it is slid back or forth so as to operate the clutch 95. One end of a link 114 is pivoted at 115 to the arm 110 and its opposite end is operatively connected to a valve 116 in the compressed air line 76. From the 10 construction above described it is apparent that the throwing in or out of the clutch 95 to start or stop the movement of the cable through the machine automatically opens or closes the passage for air to the surplus paint 15 removing device 75, the bar 112 serving to perform both functions simultaneously.

A stud shaft 120 is journaled in a bearing 121 and has keyed thereto a gear 122 which meshes with a pinion 123 keyed to the shaft 20. Rigidly secured to or forming a part of the gear 122 is a cam 124 either side of which 25 engages a roller 125 mounted in laterally extending arms 126 of a vertically disposed lever 127. The lower end of the lever 127 extends a suitable distance below the arms 126 and is pivoted at 128 to the housing 24. The lever 127 extends upwardly to approximately the top of the housing 24 and its upper end is pivoted at 129 to a horizontal bar 130. The bar 130 is slidably supported 30 in the housing 24 and carries at each end a distributing mechanism 100 which is of a well known type and comprises a pair of spaced rollers 132 suitably supported in a bracket 133. When the machine is in operation the cam 124 causes the lever 127 to reciprocate in a well known manner, which motion is transmitted through the bar 130 to the distributing mechanism 100 so as to even- 35 ly distribute the painted cable upon the take-up reel 85.

The tanks 16 are provided with openings in the top whereby the gases caused by the continuous stirring and mixing of the paint 40 are permitted to escape through an exhaust pipe 135. An exhaust hood 136 provides means for the escape of gases originating within and about the operating parts of the machine and also serves as a safety guard 45 for the operator.

The operation of the apparatus above described is as follows: The cable 60 from the supply reel 50 is threaded over the guide rollers 59 and 65, through the paint container 16 wherein it is passed under the guide roller 72, then through the wiping mechanisms 75 and 80, after which it is passed over the guide roller 82, through the distributing mechanism 100, and around the 50 take-up reel 85 to which it is suitably attached. The starting of the motor 13 causes the main driving shaft 20 to transmit motion to the pump 30 through the gearing above described. The valve 34, which controls the 55 passage of paint from an outside supply

source into the tank 15, is opened and paint is pumped into the tank 15 to a level indicated by the dotted line A in Fig. 1. During this time the valve 35 is positioned so as to close communication between the tank 15 70 and the tank 16 causing the paint which is being pumped through the pipe 33 to return to the tank 15 by way of a return pipe 19.

Upon the tank 15 being filled with paint to the level indicated by the dotted line A 75 in Fig. 1, the valve 34 is closed and the valve 35 opened thus permitting circulation of the paint from the tank 15 to the tank 16. The paint in the tank 16 is maintained at a substantially constant level indicated by the 80 dotted line B in Fig. 1. This is accomplished by properly regulating the adjustable valves 29 in the return pipes 28. The mixing member 36 is constantly driven from the main shaft 20 through the gearing above 85 described thereby maintaining the paint properly mixed during the operation of the machine. Through suitable gearing described above the distributing member 100 and also the driving member 94 of the clutch 90 90 are constantly driven from the main shaft 20. The take-up reel 85 is set into motion by pulling the bar 112 outwardly causing the driven member 99 of the clutch 95 to engage the driving member thereof. 95 Through the mechanism above described, the outward movement of the bar 112 also causes the valve 116 in the compressed air line 76 to open, thereby permitting the passage of air into the surplus paint remover 75. To 100 stop the take-up reel 85, the clutch 95 is disengaged by pushing the bar 112 inwardly, which action also operates the brake 102 to hasten the stopping of the reel. By pushing the bar 112 inwardly, the valve 116 is 105 closed, thereby shutting off the supply of air into the surplus paint remover 75.

From the above description it is apparent that starting or stopping movement of the strand through the machine operates to open 110 or close the supply of air into the surplus paint remover 75.

What is claimed is:

1. In a strand treating machine, a supply spool, a take-up spool, a receptacle containing a treating bath, means for driving the take-up spool to pass the strand through the treating bath, a wiping mechanism including means for directing a blast of air against the peripheral surface of the 120 treated strand, and common means for controlling said wiping mechanism and said driving means.

2. In a strand treating machine, a receptacle containing a treating bath, means 125 for advancing a strand therethrough, a wiping mechanism including means for directing a blast of air against the peripheral surface of the treated strand, a valve for controlling said air blast, a clutch mecha- 130

nism including a hand lever for controlling the strand advancing means, and an arm operatively connected to said hand lever for controlling the air valve.

3. In a strand working machine, a receptacle containing a treating bath, means for advancing the strand through the treating bath, means for directing a blast of air against the peripheral surface of the strand, common means for controlling the air blast and the strand advancing means, and means for maintaining the strand in a substantially straight line while being treated.

4. In a strand working machine, a receptacle containing a treating bath, means for advancing the strand through the treating bath, means for directing a blast of air against the peripheral surface of the strand, and common means for controlling the air blast and the strand advancing means.

5. In a strand working machine, a receptacle containing a treating bath, means for advancing the strand through said treating bath, means for directing a blast of air against the peripheral surface of the strand upon leaving the bath whereby the surplus treating material is removed therefrom, and common means for controlling the air blast and the movement of the strand whereby the air blast is effective only when the strand is in motion.

6. In a strand working machine, a wiping mechanism including means for directing a blast of air against the peripheral surface of a strand, means for advancing the strand through the wiping mechanism, and common means for controlling the operation of the wiping mechanism and the movement of the strand whereby the air blast is discontinued upon discontinuing the movement of the strand.

7. In a strand working machine, a receptacle containing a treating bath, the receptacle being provided with apertures in the side walls thereof below the normal level of the treating bath, means for advancing the strand through the apertures, means for continuously replenishing the treating bath to maintain the level thereof above the apertures in the receptacle, an air wiper for removing excess amounts of the treating material from the strand as it leaves the treating bath, and common means for controlling the operation of the air wiper and the movement of the strand.

In witness whereof, I hereunto subscribe my name this 30th day of July, A. D., 1924.

ROBERT ERNEST MCFARLAND.
